RAZOR HANDLE

Martin Glaberson, Stratford, Conn., assignor to
Warner-Lambert Company

Filed Apr. 18, 1975, Ser. No. 569,234

Term of patent 14 years

Int. Cl. D28—03

U.S. Cl. D95—3 A

Fig. 1

Fig. 3

Fig. 4

Fig. 2

FIG. 1 is a rear elevational view of a razor handle showing my new design;

FIG. 2 is a right side elevational view thereof, the left side being a mirror image;

FIG. 3 is a top plan view thereof; and

FIG. 4 is a bottom plan view thereof.

I claim:

The ornamental design for a razor handle, as shown and described.
